BACK GAUGE FOR PAPER CUTTER-DRIVE
DISCONNECT FOR MANUAL OPERATIONSydney Frankel, Ridgefield Park, N. J., assignor
to E. P. Lawson Co., Inc., New York, N. Y., a
corporation of New York

Application March 25, 1950, Serial No. 151,937

2 Claims. (Cl. 164—59)

1

My present invention relates to a hydraulically operated back gauge for paper cutters and more particularly to a back gauge operating mechanism adapted to move the back gauge through a series of steps to permit the cutter to perform a series of cuts on a paper stack.

This application is filed simultaneously with application Serial No. 151,936 by the same inventor and assigned to the same assignee.

For this purpose in order to obtain speed in operation, the back gauge should move rapidly between cuts. But to ensure that the paper stack will stop at an accurate predetermined cutting position for each cut, the back gauge must be slowed up just before the cutting position so that when it is brought to a stop, the paper stack will not coast beyond the stop position.

Thus, I have provided novel hydraulic back gauge operating means which will move the back gauge rapidly between cuts, will slow the back gauge down just before a cutting position is reached and halt the back gauge at the cutting position.

Where automatic drive members are provided for the back gauge, these drive members provide excessive resistance to the operation of the back gauge by hand when the back gauge is being adjusted manually to determine the proper stops for the paper stack.

Accordingly, the primary object of my invention is the provision of novel means for disconnecting the automatic drive apparatus from the back gauge when it is desired to adjust the back gauge manually.

This is particularly significant where the drive is a hydraulic one offering substantial resistance to manual operation.

The foregoing and many other objects of my invention will become apparent from the following description and drawings in which:

Figure 1 is a schematic view of the means of disconnecting the hydraulic drive mechanism from the back gauge.

Figure 2 is a side view of the cutting machine. Figure 3 is a vertical section on line 3—3 of Figure 2 through the hand wheel.

Figure 4 is a cross-sectional view on line 4—4 of Figure 3 looking in the direction of the arrows.

Figure 5 is an end view taken from line 5—5 of Figure 2 with the drive belt taut.

Figure 6 is a top view of the belt control mechanism taken from line 6—6 of Figure 5.

Figure 7 is a view corresponding to that of Figure 5 with the drive belt slack.

Figure 8 is an elevation partly in section taken

2

on line 8—8 of Figure 5 looking in the direction of the arrows.

The drive disconnect of the present invention is to be applied to the back gauge unit described in my application Serial No. 151,936, filed March 25, 1950, and assigned to the assignee of the present application.

The purpose of the present invention is to provide means automatically responsive to operation of hand wheel 210 to release the tension on belt 65 of hydraulic motor drive (see Figures 5 and 7) thereby disconnecting hydraulic motor 104 from pulley 11 and screw 204 so that the hand wheel 210 may be readily used to turn screw 204 and move the back gauge 201 and its paper pile without also being required to operate the hydraulic motor 104.

At the rear of the machine, plate 302 is secured to the underside of bed plate 100. Bracket 301 is attached to plate 302 also by bolts 290, 291.

A second bracket 303 is secured to the bottom of bracket 302 and supports the hydraulic motor 104. Driving pulley 60 is keyed to the hydraulic motor 104.

The compound V-belt pulley 64—62 is journaled on stub shaft 63 which is supported on needle bearings by belt arm 310. Belt arm 310 consists of two pieces—the upper part 310a of which carries the shaft 63 and the lower part 310b which has two trunnions 311, 312 (Figure 8), trunnion 311 being journaled on the hub 314 of the hydraulic motor casing, and trunnion 312 being provided with a ball bearing 320 on the drive shaft 321 of hydraulic motor 104.

The upper belt arm 310a is slotted at 325 to receive the tongue 326 of lower belt arm 310b. Two belt tensioning screws 327 and two clamping screws 328 are provided in the upper belt arm 310a.

Screws 328 passing through adjacent flanges of belt arm sections 310a and 310b serve to integrate the arms. Screws 327 passing through a flange of section 310a and bearing against the flange of 310b serve to space arm sections 310a and 310b by appropriate distances to maintain desired tension on belt 61.

Belt 65 as above pointed out connects pulleys 11 and 64; belt 61 connects pulleys 60 and 62.

Mounted on bracket 301 is solenoid coil 340 with armature 341 attached to plunger 342 by pin 343. Plunger 342 is guided in bracket 345 which is also fastened to bracket 301.

Anchor block 360 is also fastened to bracket 301 and link 361 is pivoted on pin 362 held in block 360.

The upper part 310a of belt arm 310 has an ear 363 extending to the left with respect to Figure 7 on which link 365 is pivoted by pin 366.

Links 365 and 361 are joined by pin 368 which fits into the slotted fork 370 of plunger 342. A stop screw 372 is threaded into ear 363 whereby links 365 and 361 may be aligned or permitted to go slightly above the horizontal when solenoid 340 is energized and arm 310 is swung to the position for tightening belt 65 shown in Figure 5.

When solenoid 340 is de-energized, tension of spring 375 on plunger 341 will break the toggle formed by links 361-365 downwardly to the position of Figure 7 and thereby pull belt arm 310 to swing to the left and slacken belt 65.

The screw 204 may now be rotated readily in either direction without any drag from hydraulic motor 104 or the associated hydraulic mechanism.

Bracket 380 is fastened to bracket 301 by screws 381 in slots 382 of bracket 380; and a screw 383 serves as an anchor for one end of spring 375. The other end of spring 375 is connected by pin 384 to slotted links 385 hung on pin 386 at the lower end of plunger 341. The purpose of the slots in links 385 is to reduce the amount of load on solenoid 340 and to provide a spring force only to break the links 361-365 into toggle relation; thereafter, belt tension and gravity will aid in slackening belt 65 and thereby disconnect screw 204 from the hydraulic motor 104 and its associated hydraulic drive elements.

The solenoid 340 of Figures 1 and 5 to 8 is energized and de-energized by the closing and opening, respectively, of the micro-switch 400 on bracket 401 supported by front bearing 206 of back gauge drive screw 204.

Micro-switch 400 is normally closed so that solenoid 340 is normally energized and the roller and stem 402 of switch 400 must be depressed to interrupt the circuit and thereby de-energize solenoid 340 to slacken belt 65.

Hand wheel 210 is arranged so that when manually rotated and pushed in, it performs this operation.

A serrated or multiple splined sleeve 410 is secured by set screws 411 to screw 204 in front of bearing 206. The hand wheel 210 has an interior bore 415 with suitable serrations or splines to cooperate with serrations and splines of sleeve 410.

The hand wheel 210 is slidably mounted on sleeve 410 and is confined between the rear washer 420 on screw shaft 204 and the front washer 421 held on shaft 204 by nut 422. Thrust bearing 425 permits relative rotation between washer 420 and bearing 206.

The spacing between washers 420 and 421 is such as to permit about $\frac{1}{16}$ inch longitudinal movement of hand wheel 210 on screw shaft 204.

Compression springs 430 (preferably four in number) in spring pockets 431 of hand wheel 210 bear against hand wheel 210 and drive it forwardly.

This drives the beveled surface 440 of hand wheel 210 away from the operating stem 402 of micro-switch 400 so that switch 400 is normally closed and the drive elements are normally in the position of Figure 5.

Whenever screw 204 is to be turned by hand, hand wheel 210 is pushed in whereby beveled surface 440 of hand wheel 210 engages the operating stem 402 of switch 400 and opens switch

400 to open the circuit to solenoid 340, thereby de-energizing the same.

As previously described in connection with Figures 5 and 7, this places the drive elements in the condition of Figure 7 so that belt 65 is slackened and the screw 204 may be manually rotated without the drag of the hydraulic mechanism.

When the hand wheel 210 is released, springs 430 drive it outwardly causing beveled surface 440 to disengage switch operator 402 and permitting switch 400 to close. This effects the operation described in connection with Figure 5 to tighten belt 65 and reconnect screw 204 with the hydraulic mechanism.

In the foregoing I have described my invention solely in connection with specific illustrative embodiments thereof. Since many variations and modifications of my invention will now be obvious to those skilled in the art, I prefer to be bound not by the specific disclosures herein contained but only by the appended claims.

I claim:

1. In a cutting machine, a cutting table, a back gauge movable along said cutting table, a longitudinal screw connected to and driving said back gauge; the invention for driving said screw which comprises a hand wheel at one end of said longitudinal screw; a first pulley secured to said longitudinal screw to drive the same; a source of power comprising a second pulley; an arm rotatably mounted about the center of rotation of said second pulley; a third pulley at the end of the arm remote from the center of rotation thereof and a first belt connection between said second and third pulley; a fourth pulley concentric with said third pulley; and a second belt connection between said fourth and first pulleys; said arm being rotatable to a position where said second belt is taut thereby permitting the transmission of power from said second to said first pulley; said arm being also rotatable to a position where said second belt is slack, thereby disconnecting said second pulley from said first pulley, said hand wheel thereby being enabled to rotate said screw free of the drag of said second pulley; solenoid means controlling the position of said arm; a switch positioned adjacent the hand wheel; said hand wheel being longitudinally movable on said end of said screw; said switch being operated by an inward movement of the hand wheel to cause said solenoid means to operate to move said arm to the slack position of the second belt.

2. In a cutting machine, a cutting table, a back gauge movable along said cutting table, a longitudinal screw connected to and driving said back gauge; the invention for driving said screw which comprises a hand wheel at one end of said longitudinal screw; a first pulley secured to said longitudinal screw to drive the same; a source of power comprising a second pulley; an arm rotatably mounted about the center of rotation of said second pulley; a third pulley at the end of the arm remote from the center of rotation thereof and a first belt connection between said second and third pulley; a fourth pulley concentric with said third pulley; and a second belt connection between said fourth and first pulleys; said arm being rotatable to a position where said second belt is taut thereby permitting the transmission of power from said second to said first pulley; said arm being also rotatable to a position where said second belt is slack, thereby disconnecting

said second pulley from said first pulley, a solenoid coil and armature; a link between said armature and said arm; said solenoid coil when energized maintaining said arm in the taut position for the second belt, a spring connected to said armature; said spring operating when the solenoid coil is de-energized to pull said armature and arm to the slack position for the second belt; the length of said arm being adjustable.
